UNITED STATES PATENT OFFICE

ALEXANDER KASK, OF SAN MATEO, CALIFORNIA

COMBINED TABLE AND BOOKCASE

Application filed April 8, 1931. Serial No. 528,662.

This invention relates to improvements in tables and has particular reference to a library table.

The principal object of this invention is to produce a table wherein a number of books may be stored in upright position, and may be concealed within the table or exposed to view, depending upon the wishes of the user.

A further object is to produce a table which will have the utility of an ordinary table and also the advantages of being able to store a quantity of books therein.

A further object is to produce a table of this character which is economical to manufacture and neat in appearance.

Other objects and advantages will be apparent during the course of the following description.

In the accompanying drawing forming a part of this specification and in which like numerals are employed to designate like parts throughout the same,

Figure 1 is a side elevation of my table,

Figure 2 is a top plan view of Fig. 1,
25 Figure 3 is a fragmentary vertical cross-section,

Figure 4 is an enlarged detail view of the operating mechanism, and

Figure 5 is a fragmentary sectional view 30 showing the locking means.

It is a well known fact that when books are carelessly laid upon a table, they are not as apt to be read as when they are held in a vertical position, wherein the titles may be easily viewed. It is also well known that it is often desired to clear a table of all books thereon so that the table may be used for other purposes.

With my device, the books are held in a vertical position where their titles are easily viewed, and further, when it is desired to remove the books from the table the book containing portion of the table may be lowered so that the top thereof is flush with the top of the table, thus presenting a clear space for whatever purpose desired.

In the accompanying drawing wherein for the purpose of illustration is shown a preferred embodiment of my invention, the numeral 5 designates the center portion of a

table top, and the numerals 6 and 7 leaves thereof. Legs are shown at 8 and 9, which legs support the top 5. Side pieces 11 extend between the legs and form a box like structure having a bottom piece 12. An opening 13 is formed in the top 5 which permits a book rack consisting of a cover plate 14 and a bottom plate 16 to be passed therethru. This book rack has braces 17 extending between the top plate and the bottom plate. A central hub 18 extending between the top plate 14 and the bottom plate 16 has a threaded member 19 secured therein. This threaded member engages a threaded shaft 21 to which is secured a bevel gear 22 which meshes with a bevel gear 23. These gears are supported by a bracket 24 upon the bottom 12. A shaft 26 extends from the gear 23 to one side of the table so that the handle 27 may be placed thereon for the purpose of rotating the shaft. In order to prevent the bottom plate of the book rack from moving beyond the surface of the table 5, I provide stops 28 (see Fig. 5). These stops are slidably carried on the bottom plate 16 and engage in recesses 29 formed upon the lower surface of the table top 5.

With this construction, it will be apparent that a plurality of books placed within the book rack as shown in Fig. 1, may be lowered to the position shown in Fig. 3, simply by rotating the handle 27, at which time the table top will be clear and can be used as a whole. When the user wishes to elevate the books where they may be viewed, the handle 27 is moved in reverse direction so as to cause the book rack to be elevated.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:—

In a table of the character described, a top having an opening therein, a book rack vertically movable thru said opening and means

for imparting relative movement to said rack with respect to said table top, said means comprising a vertically positioned threaded shaft, a threaded member secured to said book
5 rack and gears for rotating said threaded shaft for the purpose specified.

In testimony whereof I affix my signature.
ALEXANDER KASK.
